ATTORNEY

UNITED STATES PATENT OFFICE.

THEODORE G. JOHNSON, OF KANSAS CITY, MISSOURI.

FLOOR MOP.

Application filed February 24, 1925. Serial No. 11,030.

This invention relates to floor mops and the primary object thereof is to provide a swab which may be applied to the mop head without employing strings or other 5 tying devices, the swab, including a mop head receiving envelope having an opening of smaller dimensions than the dimensions of the head, the flexibility of the envelope permitting the reception of the head through 10 the opening. The swab is also provided with openings through which liquid may flow from the interior of the envelope through to the fibres which contact with the floor. By this means the swab converts 15 the mop into a fountain mop so that liquid wax, or floor dressing, can percolate through the wall of the envelope onto the fibres.

The novel construction of the invention 20 will be apparent by reference to the following description in connection with the accompanying drawings, in which

Fig. 1 is a perspective view of a mop constructed in accordance with my invention, only a fragment of the handle being 25 illustrated, and

Fig. 2 is a vertical, longitudinal, sectional view through the swab and the mop head, the handle portion and its bail being shown 30 in elevation.

The mop head is shown as comprising a skeleton structure formed by a piece of stiff wire bent into a closed, elongated loop 1 wider at the end 2 than at the end 3. Intermediate 35 the ends of the loop is a bail 4 fastened to the handle 5 in an appropriate manner, there being a transversely disposed rod or bolt 6 for fastening the bail to the main skeleton frame and the bolt is shown 40 as carrying an expansion spring 7 which exerts pressure outwardly against the side bars of the skeleton frame to maintain the shape thereof. This, however, is not a part of the present invention

It will be observed that the skeleton frame 45 in plan resembles approximately the shape of a sad-iron and that it is received within the envelope consisting of the bottom wall 8 and the top wall 9 which provides a pocket 50 10 accessible through the opening 11. The longitudinal dimension of the opening 11 is less than the longitudinal dimension of the head but by slipping the toe or small

end of the frame through the opening 11 into the deep part 12 of the pocket as far as 55 it will go and then stretching the portions 13 and 14 of the edge of the opening 11 over the enlarged part of the head the head will be received in the pocket and while there will be slight play of the head with respect 60 to the pocket, because the pocket is larger than the head, there will not be sufficient play to permit the swab and the head from becoming accidentally disassociated. The swab can be taken off the head by pulling 65 the enlarged portion longitudinally away from the enlarged portion of the head and slipping the edge portions 13 and 14 over the enlarged portion of the head and then withdrawing the remainder of the head 70 from the pocket. The bottom fly of the swab envelope is provided with rows of perforations 15 which coincide with the tufted rows or ridges 16 of fibre which contact with the floor when the mop is passed 75 over it.

The openings 15 are provided so that liquid floor dressing, for example so called liquid wax, can be flowed on to the ply 8 and feed through the openings 15 on to the 80 fibres or strands consisting of the tufted portions 16. This will afford an efficient equal distribution of the liquid over the tufted portions of the mop fabric or swab so that an equal distribution of the liquid 85 may be had over the floor surface.

It will be apparent that the swab may be constructed as inexpensively as those swabs that require strings or tapes for securing the swab to the frame or head, and that the 90 swab may be applied to the head in a much more expedient manner, furthermore it will be apparent that the equal distribution of the floor dressing over the mop and the floor will be assured.

What I claim and desire to secure by Letters-Patent is:—

1. A mop comprising an elongated mop head, a swab of corresponding shape enclosing said head, said swab comprising two 100 walls secured together to provide a pocket, said swab having an opening in one of the walls between the ends thereof provided with an uninterrupted peripheral edge portion, the length of the swab being greater 105 than the length of the mop head, the perime-

ter of the edge of the opening being more than twice the short dimension of the head, whereby the edge of the opening may be flexed over the edge of the head.

5. A swab for mops comprising a fabric having a pocket to receive a mop head, the upper face of said pocket having an opening

therein, and tufts of fibre carried by the lower face of the fabric, the fabric having perforations therethrough opposite said opening to feed liquid to the tufts. 10

In testimony whereof I affix my signature.

THEODORE G. JOHNSON.
